UNITED STATES PATENT OFFICE.

JOHN WEST, OF SOUTHPORT, ENGLAND.

DISCHARGING AND CHARGING MACHINE FOR GAS-RETORTS.

1,035,287.

Specification of Letters Patent. Patented Aug. 13, 1912.

Application filed April 9, 1910. Serial No. 554,442.

To all whom it may concern:

Be it known that I, JOHN WEST, a subject of the King of Great Britain and Ireland, residing at "The Firs," Park Road, 5 Southport, England, have invented certain new and useful Improvements in Discharging and Charging Machines for Gas- 10 Retorts, of which the following is a specification.

My invention for an improved discharging and charging machine for gas retorts has for its object to discharge the coke from the gas retorts by pushing the coke through the retort by means of a ram constructed 15 in the form of a scoop and operated by a chain, whereby the coke is discharged from the retort, and the coal fed into the retort at the same time, the coal being deposited and left in the retort when the scoop is 20 withdrawn from the retort. In order to accomplish this object I construct a telescopic ram in the form of two or more scoops, the first or outer scoop being provided with a hinged plate which, when the 25 scoop enters the retort, comes into direct contact with the coke about to be discharged from the retort. This scoop is provided with a bar extending throughout its length and fixed to the bottom of the scoop and 30 projecting beyond the scoop bottom to form a stop for the hinged plate.

The second or inner scoop is provided with a channel path for the chain operating the outward and backward stroke of the 35 scoops. One end of the chain is attached to the end of the bar in connection with the first or outer scoop and traverses when in operation the channel path of the second or inner scoop; the object of the channel path 40 being to form a casing in which the links forming the chain are kept rigid when it is pushed forward in the act of causing the scoops to enter the retort; the chain on the return stroke being kept rigid by being in 45 tension. A similar channel path is constructed on the framework of the machine, this path being of sufficient length to accommodate the total length of chain required to complete the operation.

The scoops are formed of a cross-section to suit the profile of the retort, and the number of scoops employed will depend upon the length of the retort and the available space for the machine in the retort 55 house.

At the machine end of the scoop a stop

plate is inserted and is caused to remain stationary during the time the scoops are being withdrawn from the retort.

The coke is discharged on the outward stroke of the scoops into the retort, the coal being fed into the scoop at the same time. By the first movement of the return or backward stroke the coal is compressed within the scoop and being at one end held by the stop plate the completion of the backward stroke causes the coal contained within the scoops to be deposited upon the floor of the retort, the hinged plate lifting and dragging or trailing over the coal.

When the scoops are withdrawn and the whole of the coal deposited within the retort the stop plate is released and returns into the machine.

A catch is provided for preventing the inner scoop leaving the machine on the outward stroke until the outer, or first scoop has completed its portion of the stroke and the stop plate is taken out of the machine into its position in the retort by means of a catch formed in the second or inner scoop and is returned to its position in the machine by means of another catch formed within the second or inner scoop and at the same time releasing the catch, which causes the stop plate to remain stationary during the depositing of the coal within the retort.

This invention is suitably mounted on a machine framework provided with traveling and hoisting gear for adjusting the machine to the retort to be operated upon, a coal supply hopper with feeder gear for regulating the supply of coal to the scoops and gearing for operating the scoops together with the necessary motors for same.

In order that my invention may be readily understood, I will proceed to describe the same in reference to the accompanying drawings.

Figure 1 is an end elevation of the discharging and charging machine. Fig. 2 is a plan of the discharger and charger scoop with the mechanism for actuating same. Fig. 3 is a cross-section of the telescopic scoop made up in two lengths, one telescoping into the other; the figure also shows the channel forming the chain path which is attached at one end to the inner scoop. Fig. 4 is an elevational view of the scoop. Fig. 5 is a plan view of Fig. 4. Fig. 6 is a longitudinal elevation of the scoops when telescoped into each other together with the

mechanism for controlling the order in which the scoops leave the machine to enter the retort. Fig. 7 is an end elevation of the mechanism shown in Fig. 6. Figs. 8, 9, 10, 11 and 12 are diagrammatic figures showing the action of the discharging and charging apparatus when discharging and charging a retort.

Referring to the drawings the frame *a* of the discharging and charging machine is mounted on wheels *b* which travel along rails in front of the retort bench. The discharging and charging apparatus with the telescopic scoop are suspended by a hanging frame *d* which is hoisted or lowered by the chains *e* in connection with the hoisting and traveling gear *f* which is provided with clutches so that either the hoisting or traveling gear may be put in and out of gear as may be required.

As shown in Figs 3, 4 and 5, the combined discharging and charging apparatus consists of a telescopic ram and scoops of which *g* is the outer scoop and *g*¹ the inner scoop, *h* the hinged plate or ram head; the bar *i* extends throughout the length of the outer scoop *g* and is fixed along the bottom and projects beyond same to form a stop *j* for the hinged plate *h*.

The channel path *k* for the chain *l* is secured to that portion of the second or inner scoop *g*¹ which projects beyond the scoop *g* when the two telescope, the scoop *g*¹ being longer than the scoop *g*². The end of the chain *l* is attached to the end of the bar *i* in connection with the first or outer scoop *g* and traverses, when in operation, the channel path *k* of the second or inner scoop *g*¹, the channel path *k* forming the casing in which the links forming the chain *l* are kept rigid when pushed forward in the act of causing the scoops to enter the retort. A similar channel path *k*¹ (see Figs. 4, 5 and 6) is constructed on the framework of the machine and carried around to form a path sufficiently long to accommodate the total length of chain to complete the operation. *m* (see Figs. 4 and 5) is the stop plate with bar *m*¹ which travels forward with the second scoop *g*¹ and is held stationary at the end of its forward stroke by the pawls *m*² which engage with the fixed stops *m*³ (Fig. 2) on the hanging frame *d*.

The bar *m*¹ may be constructed of two parallel bars as shown on the figures and is provided with a cross-head *n* which travels along a path *n*¹ (see Figs. 4 and 5). The bar *m*¹ to which the stop plate *m* is attached is carried forward to its position in the retort by the forward movement of the inner scoop *g*¹ which is fitted with stops *p* (see Figs. 4 and 5) which engage with the stop plate *m*, and the continued movement of the scoop drags the stop plate *m* and its bars *m*¹ with the crosshead attached to it until

it reaches the completion of the forward stroke when as before described the pawls *m*² engaging with the stops *m*³ cause the stop plate to be held against rearward movement.

The scoop *g*¹ is constructed with projecting side pieces or stops *p*.
70

The stop plate *m* with its bar *m*¹ is brought back into the machine on the return stroke of the scoops *g* and *g*¹ after they have telescoped themselves into each other, and upon the complete charge of coal being deposited in the retorts; the pawls *m*² are lifted out of the stops *m*³ by means of a projecting piece *q* (Figs. 4 and 5) fixed to the inside of the inner scoop *g*¹ which projecting piece *q* strikes the lever *q*¹ fixed to the shaft to which the pawls *m*² are secured. The stops *p* immediately afterward come in contact with the fixed stops or projecting pieces *q*² formed on the bar *m*¹ and the continued 80 backward movement of the scoops brings the stop plate *m* and its bar back into the frame of the machine.
85

In order to prevent the inner scoop *g*¹ leaving the machine on the outward stroke 90 until the outer or first scoop *g* has telescoped itself from the inner scoop *g*¹, I provide means for holding the second scoop *g*¹ in the frame of the machine; to effect this, two holes or slots *x* (see Figs. 2, 5 and 6) 95 are made in the bottom of the scoop *g*¹. These holes *x* engage with the catches *x*¹ fitted to levers *x*² fixed to a shaft *x*³ on the end of which there is a lever *x*⁴ which is operated by a cam *x*⁵ rotated by the driving 100 mechanism for pushing the scoops in and out of the retort; the cam *x*⁵ being timed to move the levers and catches *x*¹ at the proper time to release the inner scoop *g*¹.

The figures on the accompanying drawings show another set of this catch gear for holding the inner scoop; very similar to the first set and acting to hold the inner scoop *g*¹ while the outer scoop *g* telescopes into it by preventing its return to the machine 110 before its time. This second set is operated by the cam *x*⁶ driving the lever *x*⁷ which is free on the shaft *x*⁸, the shaft serving as a fulcrum for the lever (see Fig. 7).

The mechanism for driving the chain *l* 115 which puts the scoops and stop plate into motion consists of a suitable reversing motor *y* (see Figs. 1 and 2) with a train of gearing for rotating the chain wheel *y*¹ (see Figs. 2, 4, 5, and 6) engaging with the 120 chain *l*.

The Figs. 8, 9, 10, 11 and 12 are diagrammatic views which illustrate the principal actions of the discharger and charger when operating on a retort, Fig. 8 showing the 125 position of the ram discharger and scoop closed up in the machine and ready to eject the coke from the retort. Fig. 9 shows the ram head *h* pushing the coke forward and at the same time the scoops are following 130

into the retort after receiving the supply of coal from the hopper *r* when passing the outlet from this hopper. Fig. 10 shows the retort from which the coke has been ejected, also the completed forward stroke of the ram head *h* the loaded scoops *g* and *g'* and the position of the stop plate *m* which, as before described, is caused by means of pawls to be held in the frame of the machine until the scoops have delivered their charge of coal to the retort. For the convenience of illustrating the position of the scoops, the stop plate, ram head bar and chain when all are extended to their full stroke, the Fig. 10 has not been drawn with the coal in the scoops; it being understood that in this position the scoops are loaded with the coal received from the coal hopper *r* as they entered the retort.

Fig. 11 shows the scoops returning to the machine and as the coal cannot pass back owing to it being held by the temporarily fixed stop plate *m* the coal leaves the scoops and is deposited on to the floor of the retort, and in consequence, after the scoops are withdrawn, the retort will be completely charged with coal. The Fig. 11 also shows the swinging ram head or plate which hinges upward, so as to pass over the coal, the contact with the coal causing the head to partly rotate around its hinge pin.

The Fig. 12 shows the retort completely charged with coal and the discharger and scoops back into the frame of the machine as also shown in Fig. 8.

A stop is provided in the channel path *k* to prevent the scoop *g* leaving the scoop *g'* when fully extended and projections or stops are provided on the outsides of the inner scoop *g'* against which the outer scoop closes when fully telescoped on the inward stroke, the continued motion of the outer scoop *g* being thus transmitted to the inner scoop *g'*.

What I claim, and desire to secure by Letters Patent is:—

1. In a gas retort charging and discharging machine, in combination, a telescopic scoop comprising a plurality of sections, each of said sections having a channel formed in its bottom and means positioned

within said channels for operating said sections.

2. In a gas retort charging and discharging machine, in combination, a telescopic scoop comprising a plurality of sections, each of said sections having a channel formed in its bottom and a chain positioned within said channels for operating said sections.

3. In a gas retort charging and discharging machine, in combination, a frame, a telescopic scoop comprising a plurality of sections mounted upon said frame, each of said sections having a channel formed in its bottom and a chain positioned within said channels for operating said sections, said frame being provided with a pathway adapted to receive said chain and maintain it in a rigid extended position.

4. In a gas retort charging and discharging machine, in combination, a telescopic scoop comprising a plurality of sections, a catch normally holding the inner section in position until the outer section is in its extended position, a lever upon which said catch is carried, driving mechanism for operating said sections and means controlled by said driving mechanism for actuating said lever to release said catch from its holding position.

5. In a gas retort charging and discharging machine, in combination, a telescopic scoop comprising a plurality of sections, a catch normally holding the inner section in position until the outer section is in its extended position, a lever upon which said catch is carried, a second catch for holding the inner section in its extended position until the outer section is in its telescopic position, a lever upon which said second catch is carried, driving mechanism for operating said sections and means controlled by said driving mechanism for actuating said levers to release the catches associated therewith from their holding positions.

In testimony whereof I have affixed my signature, in presence of two witnesses.

JOHN WEST.
